CONDIMENT DISPENSER SET

Thomas H. Davis, Brooklyn, N. Y., assignor to Buck Enterprises, Inc., Brooklyn, N. Y., a corporation of New York

Application October 7, 1955, Serial No. 38,279

Term of patent 14 years

(Cl. D44—22)

FIG. 1

FIG. 3

Fig. 1 is a front perspective view of a condiment dispenser set embodying my novel design;

Fig. 2 is a rear perspective view thereof; and

Fig. 3 is a perspective view of one of the condiment dispensers in dispensing position.

I claim:

The ornamental design for a condiment dispenser set, as shown.
